(57) **CLAIM**

The ornamental design for a vibration therapy device, as shown and described.

DESCRIPTION

FIG. 1 is a perspective view of a vibration therapy device, showing our new design;

FIG. 2 is a front elevational view thereof;

FIG. 3 is a rear elevational view thereof;

FIG. 4 is a right side elevational thereof, the left side elevational view being a mirror image thereof;

FIG. 5 is a top plan view thereof;

FIG. 6 is a bottom plan view thereof;

FIG. 7 is a perspective view of a vibration therapy device, showing our new design;

FIG. 8 is a front elevational view thereof;

FIG. 9 is a rear elevational view thereof;

FIG. 10 is a right side elevational thereof, the left side elevational view being a mirror image thereof;

FIG. 11 is a top plan view thereof; and,

FIG. 12 is a bottom plan view thereof.

The broken lines shown in the figures are for the purpose of illustrating portions of the vibration therapy device that form no part of the claimed design.

1 Claim, 12 Drawing Sheets
